UNITED STATES PATENT OFFICE.

FLOYD P. JONES, OF TORRANCE, CALIFORNIA.

GAS ANCHOR FOR OIL WELLS.

Application filed December 11, 1926. Serial No. 154,183.

This invention relates to gas anchors for oil wells, and pertains to the provision of an effective and simple device adapted to be used in conjunction with the pump barrel and pump, for separating the gas accumulation, which occurs during a pumping operation, from the oil, and individually conserving the same.

The above recited and other objects of the invention will be more fully set forth in the following detailed description and exemplified in the accompanying drawings in which:

Figure 1 represents in diagram a vertical section through an oil well showing the application of the device.

Figure 2 is a transverse section through the same taken on the line 2—2 of Figure 1 viewed in the direction of the arrows.

Figure 3 is an enlarged side view of one of the gas anchors, parts being broken away and shown in sections to more fully bring out certain essential elements.

Figure 4 is a transverse section through the same, taken on the line 4—4 of Figure 3, viewed in the direction of the arrows.

In carrying out the invention, 5 represents the oil well or bore, 6 the well casing, 7 the pump barrel in which the usual style 30 of reciprocating pump (not shown) may be installed.

The pump barrel is provided with a bottom 8 which has threaded to its periphery a pump barrel extension or casing 9 of 35 smaller diameter than the casing 6, which projects downwardly into the well and is preferably immersed into the oil bed 10, and is provided at its lower end with a closure plug 11.

Both ends of the barrel extension 9 are provided with a plurality of oil strainer perforations 13 which open communication between the lower interior of the extension 9 and the annular chamber 14 formed between the casing and the extension, as shown.

The extension 9 is provided with a spider 15 adapted to support the lower portion of an oil conduit pipe 16 the upper end of said pipe passing through the bottom 8 of the pump barrel and communicating therewith.

Interposed in the pipe 16 and disposed between its ends are a plurality of gas anchors 17, any desired number of which may be employed, which are designed to trap the

gas in the oil and effect the separation of the gas from the oil during the pumping operation.

A gas anchor 17 is constructed to create an indirect passage for the oil in the pipe 16, and in detail comprises a U bend 18 which joins with an inverted U bend 19 to form a dome 20 which is located in a plane above the bend 18.

At the top of dome 20 is formed a valve 65 seat 21 for the reception of a ball valve 22, said ball valve being held in operative relation with its seat by means of the cage 23.

A certain amount of gas naturally escapes from the oil and passes upwardly through 70 the annular chamber 14, a great volume of gas however is mixed with the oil and is extracted therefrom by the gas anchors in the following manner.

In Figures 3 and 4 of the drawing the gas 75 anchor more nearly like it would be constructed in practice, the U bends being bunched together in a compact manner so as to permit of its insertion more readily into an annular pipe and at the same time 80 to afford a maximum capacity.

When the pump (not shown) is started, the oil is sucked from the well through the pipe 16 and being thus set in motion and agitated the gas is caused to collect into the 85 domes 20 of the gas anchors and between the piston impulses of the pump, escapes through the valves 21, passes into the extension 9 and from thence through the perforations 13 into the annular chamber 14 and 90 from thence upwardly to the top of the well, where it may be conserved in any suitable manner.

By the employment of a plurality of the gas anchors, it will be obvious that by the 95 time the oil reaches the top of the well that it will be substantially free from gas, thus obviating the necessity of later treating the oil to obtain this result.

Having thus described my invention what 100 I claim is:

1. In an oil well, an oil suction pipe; and a gas anchor interposed in said suction pipe, said gas anchor having a gas collecting dome formed thereon and a valve located in said 105 dome.

2. In an oil well, an oil suction pipe having intermittent suction impulses passing therethrough; and means interposed in said suction pipe for trapping the gas in the oil 110

going through said suction pipe during a suction impulse and permitting said gas to escape between suction impulses.

3. In an oil well, a casing; a pump barrel; a suction pipe connected to said pump barrel and extending into said casing; and a plurality of gas anchors interposed in said suction pipe, each of said gas anchors being provided with a gas trap and a valve associated with said gas trap.
4. In an oil well, a casing; a pump barrel; an oil conduit pipe communicating with said pump barrel; a second casing of smaller diameter than the first mentioned casing surrounding said conduit pipe having perfora-

tions in its wall; and a gas anchor provided with a gas trap having a valve associated therewith, interposed in said oil conduit pipe.

5. A gas anchor, comprising a conduit 20 having a gas trap formed therein and a valve associated with said gas trap.

6. A gas anchor comprising a conduit having a U shaped bend formed therein joining with an inverted U shaped bend to form 25 a gas collecting dome; and a valve mounted in said dome.

In testimony whereof I hereunto affix my signature.

FLOYD P. JONES.
